 signors to Rowe Slug Ejector Co., Ltd., Los
 Angeles, Calif., a corporation of Nevada

Application February 13, 1931. Serial No. 515,464

4 Claims. (Cl. 194—101)

This invention relates to improvements in coin selecting and detecting devices.

The general object of this invention is to provide an improved magnetic coin selector.

5 Another object of the invention is to provide an improved coin selector wherein a magnetic field or flux coacts with the force of gravity for segregating various coins or tokens.

A specific object of the invention is to provide 10 a coin selector which separates spurious coins from good coins and wherein means is provided for separating coins of various denominations and delivering them to various points.

Other objects and advantages of this invention 15 will be apparent from the following description taken in connection with the accompanying drawings wherein:

Fig. 1 is a side view of our improved coin selecting device.

20 Fig. 2 is an enlarged section taken on line 2—2 of Fig. 1.

Fig. 3 is a section taken on line 3—3 of Fig. 2.

Fig. 4 is a section taken on line 4—4 of Fig. 2.

25 Fig. 5 is an enlarged section taken on line 5—5 of Fig. 3.

Fig. 6 is an enlarged section taken on line 6—6 of Fig. 3.

Fig. 7 is a section taken on line 7—7 of Fig. 6.

30 Fig. 8 is a section similar to Fig. 5 showing a modified form of coin chute.

Fig. 9 is a similar section showing a further modified form of coin chute.

Fig. 10 is also a view similar to Fig. 5 showing a still further modified form of coin chute.

35 Fig. 11 is an enlarged fragmentary section through the housing showing a modified form of magnet arrangement.

Fig. 12 is a view similar to Fig. 11 showing a further modification of the magnet arrangement.

40 Fig. 13 is a fragmentary view similar to Fig. 3 showing a modified arrangement of the opposed magnets.

Fig. 14 is a section taken on line 14—14 of Fig. 13.

45 Fig. 15 is an end view of a modification of our invention.

Fig. 16 is a section taken on line 16—16 of Fig. 15.

50 Fig. 17 is a section taken on line 17—17 of Fig. 16.

Fig. 18 is an enlarged fragmentary view of the side of the housing shown in Fig. 16 showing the magnet in detail, and

55 Fig. 19 is a section taken on line 19—19 of Fig. 17.

Referring to the drawings by reference characters we have indicated our improved coin selecting device generally at 10. This device is adapted to be used in combination with token or coin controlled machines, change making devices 60 or can be used independently for testing coins or for other purposes.

As shown the device 10 comprises a housing 12 which is made of brass or similar material and includes side members 13 and 14. The side member 13 is provided with a front flange 15, a back flange 16, a bottom flange 17 and a top flange 18. The side member 14 is shown as secured to the side member 13 by a plurality of screws 19.

Within the housing 12 we provide guide rails 70 20 and 21 which form the bottom of a coin chute 22 and as shown the rails 20 and 21 are secured to the side member 13 by screws 21'. A member 23 which is secured to the side member 13 by screws 24 includes a guide portion 25 which forms 75 one side of a coin chute 26, a guide portion 27 which forms the bottom rail of a coin chute 28, a guide portion 29 which forms one side of a coin chute 30 and a guide portion 31 which forms the top of the lower portion of the coin chute 30. 80 The other side of the coin chute 30 is formed by a guide rail 32 which is secured to the side member 13 by screws 33 and which includes an arcuate upper guide portion 34 and an angular bottom 85 guide portion 35.

An anvil member 36 which is loosely mounted on screws 37 secured to the side member 14, includes a vertical portion 38 which forms one side of a coin chute 39 the opposite side of which is formed by the flange 15 of the side member 13. 90 The anvil member 36 further includes an inclined face 40 which forms a portion of the bottom of a coin chute 41 and a portion 42 which extends above the inclined face 40 to form a separating point. Adjacent the loose anvil member 36 we provide an anvil 43 which is rigidly secured to the side member 14 by screws 44 and which includes an angular face 45 which forms a portion of the bottom of the coin chute 41.

100 Spaced from the anvil member 43 we provide a guide rail 46 which is secured to the side member 14 by screws 47. The rail 46 includes an arcuate portion 48 which forms a portion of the bottom of the coin chute 41, a portion 49 which forms 105 one side of a coin chute 50 and a portion 51 which forms the bottom of the coin chute 50. The end of the arcuate portion 48 adjacent the anvil 43 extends above the upper surface of the arcuate portion to form a coin separating point 52 and 110

the other side of the coin chute 50 is formed by the flange 16 of the side member 13.

Spaced below the guide rail 46 we provide a guide rail 53 which is secured to the side member 14 by a plurality of screws 54 and which forms the bottom of a coin chute 55. The inner end of the guide rail 53 is spaced from the flange 15 of the side member 13 and includes an upwardly extending portion which forms a coin separating point 56.

Spaced from the inner end of the guide rail 53 we provide an anvil member 57 which is rigidly secured to the side member 14 by screws 58 and which forms the bottom of the coin chute 39.

16 In the coin chute 22 we provide a magnetic member which is shown in the form of a horseshoe magnet 60 which is positioned in a similarly shaped aperture in the side member 13 and is secured to the side member 13 by a cross bar 61, a 20 bolt 62 and a nut 63 (see Figs. 1, 3 and 4). The poles of the magnet 60 form portions of the bottom of the coin chute 22 and are flush with the upper surface of the guide rails 20 and 21.

At the portion 35 of the coin chute 30 we provide 25 a pair of opposed magnet members 65 which are shown as of the horseshoe type. As shown the pole ends of the magnets are positioned in apertures 66 provided in the side members 13 and 14 and are flush with the inner faces of the side 30 members. As shown the magnets 65 are mounted on lips 67 turned out from the side members and clamped to the lips by bars 68 and 69 and screws 70. The magnetic members 65 may each be one solid piece as shown or they may be each made up 35 of a plurality of separate magnetic members.

The members 20 and 21 of the coin chute 22 are inclined downward from the front flange 15 and are adapted to direct tokens onto the portion 27 of the coin chute 28.

40 In the coin chute 26 we provide an aperture 72 in the side member 13. The top of the aperture 72 is positioned below the upper surface of the guide rails 20 and 21 and below the upper surface of the portions 27 of the member 23. On the side 45 of the aperture 72 adjacent the magnet 60 an in-turned flange 73 is provided. The aperture 72 opens into a coin chute 75 which is formed by an upper guide rail 76 which is secured to the side member 13 by countersunk screws 77 and a lower guide rail 78 which is secured to the side member 13 by countersunk screws 79 (see Fig. 4). The coin chute 75 includes an inclined portion 80 which is adapted to direct tokens towards a coin chute 81. Arranged at an angle to both the coin chute 80 and the coin chute 81 we provide a coin chute 82.

The coin chute 82 is formed by an upper guide rail 83 which is secured to the side member 13 by a plurality of countersunk screws 84 and by 60 a lower guide rail 85 which is secured to the side member 13 by countersunk screws 86. The coin chute 82 includes a curved portion 87 which is adapted to direct tokens into a coin chute 88. One side of the coin chutes 75, 80, 81 and 82 is 65 formed by the side member 13 and the other side of these coin chutes is formed by a plate 90 which is secured to the guide rails by screws 91 and which include side flanges 92, 93, and 94, of which the flange 92 forms one side of the coin chute 81.

70 In the side member 13 and in the coin chute 39 we provide an aperture 95 which opens into the coin chute 81. The upper edge of the aperture 95 is spaced below the coin separating point 42 of the anvil 36 and below the upper edge of 75 the guide rail 85.

In the side member 13 and in chute portion 41 between the anvil 43 and the guide rail 46 we provide an aperture 96 which opens into the coin chute 88. The upper edge of the aperture 96 is below the upper surface of the anvil 43, below the coin separating point 52 and below the upper portion of the guide rail 85.

Between the anvil 57 and the guide rail 53 an aperture 97 is provided in the side member 13 which opens into the coin chute 88. The upper edge of the aperture 97 is positioned below the upper surface of the anvil 57 and below the coin separating point 56 of the guide rail 53.

80 Coins or tokens are adapted to pass from within the housing 12 through the aperture 72 into the coin chute 75 and from within the housing through the apertures 96 and 97 into the coin chute 88 while coins or tokens are adapted to pass from the coin chute 81 through the aperture 95 into the housing 12.

85 In Figs. 6 and 7 we have shown one means for directing the coins or tokens through the apertures 72, 95, 96, and 97. In these figures the means for directing coins or tokens through the aperture 96 is illustrated but the same means is 90 used in connection with all the apertures mentioned. In the side member opposite to that in which the aperture is provided we stamp therefrom a tongue 98, the lower end of which is bent across the coin chute and positioned in the aperture through which the coin is adapted to pass. Where guide rails or other objects are not positioned adjacent the aperture we provide side flanges 99 which are bent inwardly from the side 95 members in which the aperture is positioned.

100 In the portion 80 of the coin chute 75 we provide a magnet member 100 which is shown as of the horseshoe type. This magnet is positioned in an aperture in the plate 90 and is secured thereto by a cross bar 101 and a screw 102. The 105 pole ends of the magnet 100 are flush with the working surface of the guide rail 78 and the lower side 103 of the magnet is flush with the guide rail 83 of the coin chute 82. The lower corner of the 110 pole of the magnet is rounded into the lower side 103 as indicated at 104.

115 Coins or tokens are shown as adapted to be delivered to the coin chute 22 by a coin chute 105 and spurious coins or tokens are adapted to be directed from the coin chute 88 away from the 120 device 10 through a coin chute 106. Certain good coins are adapted to be directed from the coin chute 41 into a coin chute 107, others from the coin chute 50 into a coin chute 108 and still others from the coin chute 55 into a coin chute 109. 125 The coin chutes 107, 108 and 109 may direct the 130 coins to coin actuated mechanisms such as when the device 10 is used in a vending machine or merely to separate compartments such as when the device is used in a change making machine. 135

140 As stated the device 10 is adapted to separate good coins or tokens from spurious coins or tokens and to separate good coins or tokens of different denominations. As shown the device 10 is adapted to separate spurious coins or tokens from United States twenty five cent, ten cent and five cent pieces, and Canadian five cent pieces.

145 In operation all coins are delivered through the coin chute 105 to the coin chute 22 which directs them towards the coin chute 28. Spurious coins or tokens which contain ferrous material will, when they pass over the magnet 60, be subjected to the influence of the magnet so that their speed will be reduced and they will follow around the side of the magnet into the coin chute 26 and as 150

they pass downward they contact with the flange 73 and become disengaged from the magnet 60 whereupon they pass through the aperture 72 into the coin chute 75. The strength of the magnet 60 is insufficient to cause tokens containing ferrous material to adhere thereto in defiance of gravity. As Canadian nickels contain a ferrous material they will be directed through the aperture 72 into the coin chute 75 along with ferrous slugs.

10 All non-ferrous coins or tokens will not be slowed down by the magnet 60 and will jump the gap formed by the coin chute 26 onto the portion 27 in the coin chute 28. The portion 27 of the coin chute 25 is inclined upward from the coin chute 26 towards the entrance to the coin chute 30 to slow the coins down so that they will not strike the guide rail 32 with sufficient force to cause them to rebound and roll back into the coin chute 26. From the coin chute 28 the coins or tokens 15 pass down the coin chute 30 to the inclined portion 35. A good twenty five cent piece upon leaving the coin chute 30 will strike the anvil 45, rebound and jump the gap between the anvil 45 separating point 52 and roll along the portion 48 and the guide rail 46 and pass over the coin separating point 52 and the coin chute 107.

As the coin chute 50 is substantially equal in width to the diameter of a ten cent piece, the twenty-five cent piece will pass thereover into the coin chute 107. A good ten cent piece upon leaving the coin chute 30 will follow the same course as the twenty-five cent piece until it reaches the coin chute 50 whereupon it will fall down the coin chute 50 and will be directed into the coin chute 108 by the portion 51 of the guide rail 46. As a United States nickel or five cent piece passes the magnets 65 the eddy currents set up by the nickel piece rolling through the flux field will effect the velocity of the piece in a manner whereby the force of gravity will cause it to pass to the coin chute 39 and strike the anvil 57, rebound and jump the gap between the anvil and the guide rail 53 and pass over the coin separating point 56 into the coin chute 55 whereupon it will roll along the guide rail 53 and into the coin chute 109.

As some spurious twenty-five cent and ten cent pieces pass the magnets 65 the eddy currents set up by the coins rolling through the flux field will effect the velocity thereof in a manner whereby the gravity will direct them downward between the anvil and the separating point 52 whereupon they will pass through the aperture 96 into the coin chute 88. Still other spurious twenty-five and ten cent pieces will be affected by the eddy currents as they pass through the flux field of the magnets which will effect the velocity thereof in a manner whereby the force of gravity will direct them to strike the loose anvil 36. As the anvil 36 is loosely supported the momentum of the spurious coins will be damped upon striking the anvil 36 and will pass over the face 45 of the anvil 43 and pass through the aperture 96 into the coin chute 88.

From the foregoing description it will be apparent that all good United States twenty-five and ten cent pieces will be directed to strike the anvil 43, rebound and pass over the coin separating point 52 and pass along the portion 48 of the guide rail 46 from which the twenty-five cent pieces pass into the coin chute 107 and the ten cent pieces into the chute 50 and thence to the coin chute 108. And that all good U. S. five cent pieces are directed to pass over the coin separating point 42 and pass down the coin chute 39, strike the anvil 57 and rebound and pass over the coin

separating point 56 and pass along the guide rail 53 to the coin chute 109.

The spurious coins and tokens which contain ferrous material and Canadian nickels upon entering the coin chute 75 roll therealong and pass the magnet 100 in the portion 80. The magnet 100 is of a strength which will attract the ferrous material of a Canadian five cent piece with such little force that the force of gravity readily overcomes the magnetic force at the same time the magnetic strength of the magnet 100 is such that the force of gravity does not so readily overcome the magnetic force on spurious coins containing more ferrous material than a Canadian nickel.

Thus when a Canadian nickel passes the magnet 100 the force of gravity causes it to fall into the coin chute 81 and thence through the aperture 95 into the coin chute 39 and thereafter it follows the same course as the U. S. nickel.

As the more ferrous spurious coins pass over the poles of the magnet 100 the force of gravity carries them downward but the magnetic force causes them to adhere to the side 103 of the magnet and they roll therealong until they engage the guide rail 83 of the coin chute 82 whereupon they pass along the coin chute 82 and thence into the coin chute 88.

As shown, half of the magnet 100 is positioned on the inside of the plate 90 and half on the outside thereof. Across the poles of the magnet 100 on the outside of the plate 90 we provide a keeper 110 which is shown as secured to a lip 112 on the cross bar 101 by a screw 113. The screw 113 is positioned in an elongated aperture 114 in the lip 112 so that the keeper may be moved to various positions on the poles to adjust the magnetic force of the magnet on the ferrous tokens.

When the coins pass the magnets 65 it is desirable that they have the same relation thereto at all times and as the coin chute 30 is of a thickness sufficient to allow a twenty-five cent piece to pass therethrough there is more than enough room for a ten cent piece which might never pass the magnets in approximately the same position. To cause the ten cent pieces to all pass the magnets 65 in approximately the same position we bevel the portion 35 of the guide rail 32 as indicated at 116 and clearly shown in Fig. 5. By so beveling the portion 35 all of the ten cent pieces are directed towards one of the magnets 110 115 120 125 65 and thus they all pass the magnets 65 in approximately the same position.

In Fig. 8 we have shown the portion 35 of the guide rail 32 as provided with a V shaped groove 117 which will cause the ten cent pieces to be 130 inclined towards one magnet or the other as indicated by the dotted lines. Thus as the ten cent pieces pass the magnets they all have approximately the same relation thereto.

In Fig. 9 we have shown the portion 35 of the 135 guide rail 32 as provided with a straight sided groove 118 with the edges thereof beveled as indicated at 119. As the ten cent pieces pass the magnets 65 in this instance they are positioned in the groove 118 and are retained in a vertical 140 position midway between the opposed magnets 65 thus all ten cent pieces pass the magnets in the same relation thereto.

In Fig. 10 we have shown the portion 35 of the guide rail 32 provided with an elliptically shaped 145 groove 120 and with shoulders 121 on each side thereof. As a ten cent piece passes the magnets 65 in the groove 120 it is tilted towards one magnet or the other similar to the ten cent pieces as they pass along the groove 117 shown in Fig. 8. 150

Twenty five cent pieces and five cent pieces do not enter the groove 120 but pass thereover on the shoulders 121.

Instead of using the pair of opposed magnets 65 we may use a single magnet 125 which is positioned on one side of the coin chute with a keeper 126 opposite therefrom as shown in Fig. 11. Coins or tokens rolling between the magnet 125 and the keeper 126 will set up eddy currents in 10 the flux field which will affect the coin or token in a manner similar to that described in connection with the magnets 65.

In Fig. 12 we have shown a modification of the magnet and keeper arrangement wherein a magnet 127 positioned on one side of the coin chute is similar to the magnets 65, and a keeper 128 is positioned on the opposite side of the coin chute. The keeper 128 includes spaced ends 129 which are positioned in apertures 130 in the side member 20 and which are directly opposite the poles of the magnet 127. With this type of keeper the flux field extends across the coin chute from the poles of the magnets to the associated ends of the keeper in a manner similar to that when the 25 opposed magnets 65 are used.

In Figs. 13 and 14 we have shown a modification of the arrangement of the opposed magnets wherein a pair of horseshoe magnets 131 are arranged in the portion 35 of the coin chute 30 at 30 right angles to the position of the magnets 65. As shown the pole ends of each of the magnets 131 are positioned in longitudinal alignment with the coin chute with one pole adjacent the top of the coin chute and the other adjacent the bottom of 35 the coin chute. The action of the coins or tokens as they pass through the flux field of the magnets 131 is the same as previously described in connection with the magnets 65.

In Figs. 15 to 19 inclusive we have indicated 40 generally at 135 a modification of our device wherein a portion of the device 10 is used as a single unit for separating Canadian nickels from U. S. nickels and spurious coins.

As shown the device 135 comprises a housing 45 136 which includes a side member 137 and a side member 138. The side member 137 includes upper and lower inturned flanges 139 and 140 and inturned side flanges 141 and 142 and the side member 138 is secured to the side member 137 by 50 a plurality of screws 143.

Within the housing 136 we provide an inclined coin chute 145 which includes a guide rail 146, secured to the side member 137 by a plurality of screws 147 and a guide rail 148 which is secured to the side member 135 by a plurality of 55 screws 149.

At an angle to and communicating with the coin chute 145 we provide another coin chute 150, a portion 151 of which is approximately at right 60 angles to the coin chute 145, and a portion 152 of which is approximately vertical. The coin chute 150 includes a guide rail 153 which is secured to the side member 137 by a plurality of screws 154 and a guide rail 155 which is secured 65 to the side member 137 by a plurality of screws 156.

Adjacent the side of the housing 136 opposite the coin chute 150 we provide a coin chute 158 which is approximately vertical and at its upper 70 end communicates with the coin chute 145 and at its lower end communicates with a coin chute 159 with which the coin chute 150 also communicates. One side of the coin chute 158 is formed by a guide rail 160 which is secured to the side member 138 by a plurality of screws 161 and the

opposite side is formed by the flange 142 of the side member 137. The upper end of the guide rail 160 is preferably beveled to correspond to the angle of the coin chute 145 and to form a coin separating point 162.

The coin chute 159 includes a bottom guide rail 163 which is secured to the side member 138 by a plurality of screws 164 and is inclined from the horizontal and includes a curved upper face portion 165 which rounds into the coin chute 158.

Positioned between the coin chute 150 and the coin chute 158 we provide an aperture 166 in the side member 137. One side of the aperture 166 is in line with the juncture of the upper side of the coin chute with the coin chute 145 and the top of the aperture is below the angular portion 151 of the coin chute 150.

The upper portion of the guide rail 155 of the coin chute 150 terminates in line with the adjacent side of the aperture 166 and includes a coin separating point 167.

The aperture 166 opens into a coin chute 168 which is formed by a housing 169. To direct coins or tokens through the aperture 166 we provide a tongue 170 which is stamped out of the side member 138 and bent across the space between the side members 137 and 138 with the lower end thereof positioned in the aperture 166 (see Figs. 17 and 19). On the side of the aperture 166 opposite the guide rail 160 we provide a flange 171 105 which is formed from the material of the side member 137 and is bent inwardly towards the side member 138.

At the juncture of the upper portion of the coin chute 150 with the coin chute 145 we provide a magnetic member 172 which is shown as of the horseshoe type. The magnet 172 is positioned in a similarly shaped aperture in the side member 137 with half of the magnet within the housing and half outside and with the pole ends of 110 the magnet flush with the working face of the guide rail 146 of the coin chute 145.

The lower side 173 of the magnet 172 is arranged at the same angle as the angular portion 115 151 of the coin chute 150 and forms an upper guide rail therefor and the guide member 153 includes an arcuate working face 174 which curves into line with the side 173 of the magnet. The magnet 172 is shown as secured to the side member 137 by a cross bar 175 and a screw 176.

Across the pole ends of the magnet 172 on the outside of the side member 137 we provide a keeper 177 which is shown as secured to a lip 178 on the cross bar 175 by a screw 179. The screw 179 is positioned in an elongated aperture 180 in the lip 178 so that the keeper may be moved to various positions on the poles to adjust the magnetic force of the magnet on ferrous coins or tokens.

For delivering coins or tokens to the coin chute 145 we provide a coin chute 182 and for conveying coins or tokens away from the housing 136 we provide a coin chute 183.

As shown the device 135 is adapted to separate spurious coins or tokens and U. S. nickels from Canadian nickels.

In operation the coins or tokens are delivered through the coin chute 182 to the coin chute 145 which directs them downward past the magnet 172. All non-ferrous coins as they roll down the coin chute 145 gain sufficient velocity to jump the gap between the magnet 172 and the coin separating point 162 and pass over the coin separating point 162 into the coin chute 158. Thus non-ferrous slugs and U. S. nickels enter the coin 13.

- chute 158 and pass to the coin chute 159 and thence into the coin chute 183. As coins or tokens containing ferrous material pass the magnet 172 the magnetic force thereof acts against the action 5 of gravity and slows them down an amount dependent upon the quantity of ferrous material contained therein. The magnetic strength of the magnet 172 is so adjusted that when Canadian five cent pieces pass the lower pole of the magnet 10 the force of gravity thereon will overcome the magnetic attraction and the Canadian five cent piece will fall vertically and pass between the coin separating points 162 and 167 and pass through the aperture 166 into the coin chute 168.
- 15 Coins or tokens containing more ferrous material will, as they pass the lower pole of the magnet 172, continue to be attracted to the magnet with such force that the force of gravity does not entirely overcome the magnetic force but 20 causes the coins or tokens to roll downward along the side 173 of the magnet. When the coins or tokens engage the guide rail 153 the force of gravity thereon overcomes the magnetic force and the coins fall into the vertical portion 152 of the coin chute 150 and thence into the coin chute 159 which directs them into the coin chute 183.
- Throughout the specification and claims we have used the word "ferrous" as typical of all para-magnetic coins or tokens and the word 30 "non-ferrous" as typical of all dia-magnetic coins or tokens.
- From the foregoing description it will be apparent that we have provided a novel coin selector which is simple in construction and highly efficient in use.
- Having thus described our invention, we claim:
1. In a coin separator, a housing, a coin chute in said housing, said coin chute being inclined, means to deliver coins to said coin chute, a second 40 coin chute in said housing spaced from said first coin chute to form a gap therebetween, said second coin chute being positioned below said first coin chute and being inclined opposite to said first coin chute, a magnetic member associated 45 with said first coin chute and positioned adjacent said gap, said magnet being adapted to cause ferrous coins to fall through said gap between said first and second coin chutes, non-ferrous coins being adapted to jump said gap from said 50 first coin chute to said second coin chute, a third coin chute, said third coin chute communicating with said second coin chute and being inclined at a sharper angle than said second coin chute, a pair of opposed magnetic members associated 55 with said third coin chute, said magnets being of the horseshoe type with their poles associated with the side walls of said third coin chutes, a fourth coin chute in said housing positioned below said third coin chute, a gap in said fourth coin chute, there being an aperture in said housing adjacent said gap, a rigid anvil adjacent one side of said gap in said fourth coin chute, a guide rail in said fourth coin chute having a coin separating point adjacent said gap, a loosely mounted 60 anvil adjacent said rigid anvil, said opposed magnets being adapted to affect certain good coins in a manner whereby the force of gravity will cause said good coins to strike said rigid anvil and rebound and jump said gap in said fourth coin chute, said opposed magnets being adapted to affect certain spurious coins in a manner whereby the force of gravity will cause them to enter the gap in said fourth coin chute and pass through said 65 aperture, other spurious coins being affected by said opposed magnets in a manner whereby the force of gravity causes them to strike the loose anvil thereby damping the momentum thereof so that said other spurious coins cannot jump said gap in said fourth coin chute, a sixth coin chute in said housing arranged at an angle to said fifth coin chute, an anvil in said fifth coin chute, a guide rail in said sixth coin chute spaced from said anvil in said fifth coin chute to form a gap therebetween, there being an aperture in said housing adjacent said gap in said sixth coin chute, good coins in said fifth coin chute being adapted to strike said anvil and jump said gap and pass over said coin chute, spurious coins in said fifth coin chute being adapted to strike said anvil in a manner whereby the force of gravity will cause them to pass through said gap in said sixth coin chute and pass through said associated aperture.
2. In a coin separator, a housing, a coin chute in said housing, said coin chute being inclined, means to deliver coins to said coin chute, a second coin chute in said housing spaced from said first coin chute to form a gap therebetween, said second coin chute being positioned below said first coin chute and being inclined opposite to said first coin chute, a magnetic member associated with said first coin chute and positioned adjacent said gap, said member being adapted to cause ferrous coins to fall through said gap between said first and second coin chutes non-ferrous coins being adapted to jump said gap from said first coin chute to said second coin chute, a third coin chute, said third coin chute communicating with said second coin chute and being inclined at a sharper angle than said second coin chute, a pair of opposed magnets associated with said third coin chute, a fourth coin chute in said housing positioned below said third coin chute, a gap in said fourth coin chute, there being an aperture in said housing adjacent said gap, a rigid anvil adjacent one side of said gap in said fourth coin chute, a guide rail in said fourth coin chute having a coin separating point adjacent said gap, a loosely mounted anvil adjacent said rigid anvil, said opposed magnets being adapted to affect certain good coins in a manner whereby the force of gravity will cause said good coins to strike said rigid anvil and rebound and jump said gap in said fourth coin chute, other good coins being affected by said opposed magnets in a manner whereby the force of gravity will cause said other good coins to pass over said coin separating point on said loose anvil and enter said fifth coin chute, said opposed magnets being adapted to affect certain spurious coins in a manner whereby the force of gravity will cause them to enter the gap in said fourth coin chute and pass through said aperture, other spurious coins being affected by said opposed magnets in a manner whereby the force of gravity causes them to strike the loose anvil thereby damping the momentum thereof so that said other spurious coins cannot jump said gap in said fourth coin chute, a sixth coin chute in said housing arranged at an angle to said fifth coin chute, an anvil in said fifth coin chute, a guide rail in said sixth coin chute spaced from said anvil in said fifth coin chute to form a gap therebetween, there being an aperture in said housing adjacent said gap in said sixth coin chute, good coins in said fifth coin chute being adapted to strike said anvil and jump said gap and pass over said coin chute, spurious coins in said fifth coin chute being adapted to strike said anvil in a manner whereby the force of gravity will cause them to pass through said gap in said sixth coin chute and pass through said associated aperture.
3. In a coin separator, a housing, a coin chute in said housing, said coin chute being inclined, means to deliver coins to said coin chute, a second coin chute in said housing spaced from said first coin chute to form a gap therebetween, said second coin chute being positioned below said first coin chute and being inclined opposite to said first coin chute, a magnetic member associated with said first coin chute and positioned adjacent said gap, said magnetic member being adapted to cause ferrous coins to fall through

said gap between said first and second coin chutes, non-ferrous coins being adapted to jump said gap from said first coin chute to said second coin chute, a third coin chute, said third 5 coin chute communicating with said second coin chute and being inclined at a sharper angle than said second coin chute, a pair of opposed magnetic members associated with said third coin chute, said magnets being of the horseshoe type 10 with their poles forming a portion of the side walls of said coin chute, a fourth coin chute in said housing positioned below said third coin chute, a gap in said fourth coin chute, and an aperture in said housing adjacent said gap, a 15 rigid anvil adjacent one side of said gap in said fourth coin chute, a guide rail in said fourth coin chute having a coin separating point adjacent said gap, a loosely mounted anvil adjacent said rigid anvil, said loose anvil having a coin 20 separating point thereon, a fifth coin chute adjacent said loose anvil, said opposed magnets being adapted to affect certain good coins in a manner whereby the force of gravity will cause good coins to strike said rigid anvil and rebound 25 and jump said gap in said fourth coin chute, other good coins being affected by said opposed magnets in a manner whereby the force of gravity will cause said other good coins to pass over said coin separating point on said loose anvil 30 and enter said fifth coin chute, said opposed magnets being adapted to affect certain spurious coins in a manner whereby the force of gravity will cause them to enter the gap in said fourth coin chute and pass through said aperture, other 35 spurious coins being affected by said opposed magnets in a manner whereby the force of gravity causes them to strike the loose anvil thereby damping the momentum thereof so that said other spurious coins cannot jump said gap in 40 said fourth coin chute.

4. In a coin separator, a housing, a coin chute

in said housing, said coin chute being inclined, means to deliver coins to said coin chute, a second coin chute in said housing spaced from said first coin chute to form a gap therebetween, said second coin chute being positioned below said first coin chute, a magnetic member associated with said first coin chute, said magnet being adapted to cause ferrous coins to fall through said gap between said first and second coin chutes, non-ferrous coins being adapted to jump said gap from said first coin chute to said second coin chute, a third coin chute communicating with said second coin chute and a magnetic member associated with said third coin chute, said magnet being of the horseshoe type with the pole associated with the side wall of said third coin chute, a fourth coin chute in said housing positioned below said third coin chute, a gap in said fourth coin chute, there being an aperture in said housing adjacent said gap, an anvil adjacent one side of said gap in said fourth coin chute, a guide rail in said fourth coin chute having a coin separating point adjacent said gap, a second anvil adjacent said first anvil, said horseshoe magnet being adapted to affect certain good coins in a manner whereby the force of gravity will cause them to enter the gap in said fourth coin chute and pass through said aperture, other spurious coins being affected by said opposed magnets in a manner whereby the force of gravity causes them to strike the second anvil thereby damping the momentum thereof so that said other spurious coins cannot jump said gap in said fourth chute.
